UNITED STATES PATENT OFFICE.

HENRY SELLMAN, OF BROOKLYN, NEW YORK.

BALL-MILL.

1,363,620.

Specification of Letters Patent. Patented Dec. 28, 1920.

Application filed February 26, 1920. Serial No. 361,599.

To all whom it may concern:

Be it known that I, HENRY SELLMAN, a citizen of the United States, and a resident of Brooklyn, in the county of Kings and State of New York, have invented certain new and useful Improvements in Ball-Mills, of which the following is a specification.

This invention relates to ball or pulverizer mills, and especially to that class in which a rotatable drum is provided with an upper charge opening and a lower discharge opening controlled by a suitable valve.

The chief object of my invention is to provide a pulverizer drum with such facilities for being charged with raw materials and discharging treated matter as to considerably reduce the time and labor involved, and to entirely eliminate the danger of dropping dirt or raw material into a batch of finished material.

Further objects will appear as this specification proceeds.

In the accompanying drawings,

Figure 1 is a longitudinal, sectional view 25 of an apparatus embodying the present invention.

Fig. 2 is a central, transverse section of the same apparatus.

Fig. 3 is an enlargement of a portion of 30 Fig. 1.

Fig. 4 is an enlarged plan view of part 5 illustrated in Figs. 1 and 2.

Fig. 5 is a central view of Fig. 4 in longitudinal section.

Fig. 6 is an enlarged view of part 11 of 35 Fig. 1.

Fig. 7 is a plan view of Figs. 3 and 6 assembled.

Fig. 8 is a view of part 28 of Figs. 4 40 and 5.

Throughout the views the same reference characters refer to the same parts.

In attrition mills for grinding different materials in liquid media of various kinds, 45 it has been customary to stop the mill when the grinding was finished so that the charge intake cover would be on top. This cover would then be replaced by a special discharging cover, after which the drum would 50 be turned half a revolution to locate the dis-

charge cover in its lowest position and the contents drained off. If the pulverized matter is of a very viscid consistency, this method will not avail to withdraw the contents satisfactorily from the mill.

55

It is one of the chief aims of my invention to facilitate the efficient withdrawal of all such liquids and pastes from the mill.

Referring again to the drawings, the castings 1 and 2 are provided with aligned shafts 60 or trunnions 13 and 14, and with peripheral flanges secured within the extremities of the annular sheet 3 by welding, sweating or by means of rivets, according to the choice of the manufacturer.

65

Surmounting the apparatus is shown the charging cover 12, secured in position by swing bolts and nuts 15. The pebbles or balls used in the apparatus have been omitted to clarify the views. However, in order 70 to protect material to be ground from being contaminated, and to assist in the grinding operation, the usual porcelain or other lining 10, 19 and 20 has been provided.

Diametrically opposite the charging cover 75 12 is the special discharge valve 5 which provides the chief advantages of my invention. The valve casing 5 is intended to be permanently secured to the drum in contrast with the charging cover; and contains 80 a drain chamber 7, which latter has an inclined floor to cause gravitation of liquid toward outlet 24, the cap 25 normally closing this outlet. While the valve is ordinarily a permanent part of the drum and is 85 never removed in the course of operating the mill, yet it may be necessary to occasionally remove it to renew worn parts, but its permanent character in the matter of its location is one of its chief advantages. 90 In order to prevent any of the balls inside the drum from dropping out, a strainer disk 28 has been inserted in the valve, and is provided with a plurality of moderately large orifices 26, presenting minimum resistance 95 to ground stock when it is desired to draw off the same.

When the mill is in operation, the mentioned orifices in disk 28 are covered by the sector plate 23, which is adapted to turn 100

with valve stem 6 when hand wheel 8 is rotated, this result being insured by the insertion of a pin 34 which passes through stem 6 and lies in a slot in the sector plate. Its possible movement is but a quarter revolution, inasmuch as the pin or stud 27 on the sector plate is limited between pins 32 and 33 in the channel 9 of the strainer disk. Thus it is evident that the sector plate is both normally in contact with the strainer disk and is limited to accurate open and closed positions in relation to said disk.

However, it may be found advantageous, at times, to slightly lift the sector plate without turning it, and by this means uncovering the strainer disk. The construction of the valve permits this, for while the washer 29 is pressed down upon the collar 16 by contact with a gland 18, thereby retaining the plate 23 in normal contact with strainer disk 28, the washer, it will be noted, is actually a coil spring of one turn. It is only necessary to loosen set screw 17 and secure the collar 16 a little lower on the valve stem 6 after having substituted a regular coil spring for washer 29, and the plate 23 may be lifted very considerably, thereby exposing the openings in the disk.

As an auxiliary means to assist in the operation of discharging, an air nipple or inlet 4 has been provided in the cover 12. When the drum is rotated, the plug 11 prevents any leakage by stopping the air vent in 4. More detailed, the plug has a threaded portion 31 to fit the thread in nipple 4, the flange 30 acting as an air tight stop, while shank 21 completely fills the orifice 22 in the porcelain lining of the cover 12.

In the operation of the mill, the swing bolts 15 are loosened and cover 12 removed. Granting that a quantity of balls are present in the drum, crude matter to be treated is introduced in sufficient quantity to constitute a charge, with the possible addition of a liquid such as water, oil or similar media. The cover is replaced, and the plug 11, cap 25, and gland 18 are tested to see that they are tight, as well as valve 5, to see that plate 23 is closed. The drum is then rotated the proper length of time till the charge is ground.

When the mill is stopped in original position, the outlet cap 25 is removed, likewise vent plug 11, and the valve stem 6 turned to open the valve. In case the contents flow indifferently because of their being too viscid, an air hose may be screwed to either the outer or the inner threads of nipple 4 and the pressure will quickly empty the mill. Water may also be used to wash out the contents by connecting a suitable hose or pipe to the same nipple.

When empty, the drum will be ready for a fresh charge by merely closing the valve,

replacing the cap 25, vent plug 11 and opening cover 12. After being again charged, the mill will be ready to grind once more.

Having thus fully described my invention, I claim:

1. A pulverizer drum provided with an outlet valve having a chamber therein in the peripheral wall thereof, a valve stem extending from the outer portion of said valve through the casing of the latter, the chamber in said casing communicating with an exterior nipple, a strainer plate having perforated sections connecting the interior of said drum with said valve chamber, and a sector plate secured to the inner extremity of said valve stem and adapted to move across the perforations in said strainer disk upon rotation of said valve stem.

2. In a pulverizer drum, a discharge valve having a chamber therein provided with an exterior nipple, a sector valve stem passing through said valve provided upon its inner extremity with a sector disk to move therewith, and upon its outer extremity with manually operative means, a collar secured upon said outer stem extremity with said manual means, and a coiled compression spring located upon said valve stem between said collar and the casing of said valve, permitting rotation of said disk in contact with the inner extremity of said valve casing and also axial movement therefrom.

3. In a pulverizer drum a gravity valve casing provided with a disk covering the chamber in said casing, there being perforations in said disk and a shoulder in the upper portion of said chamber to support said disk, a sector plate upon said disk in contact therewith and concentric with the same, a discharge pipe in said valve casing communicating with its interior and provided with a cap, the floor of said chamber being inclined from the extreme perforations in said disk toward said discharge pipe, and a manually rotatable valve stem passing through said valve casing, disk and plate to rotate one of the latter two in relation to the other.

4. A pulverizer drum including a valve in the peripheral wall thereof having a perforate disk covering the interior chamber thereof, a sector plate upon said disk and a rotatable valve stem adapted to move one of said contacting parts in relation to the other to cover the perforations in said disk, and means to limit said relative movement including in the disk a channel having a pair of limit pins secured therein and a pin projecting from said plate into said channel between said limit pins.

5. A mill drum including a valve in the wall thereof, a disk covering the chamber in said valve, said disk being supported by the casing of said valve and provided with

perforated sections, a sector plate concentrically located upon said perforated disk, a valve stem extending through said valve casing and said disk and sector plate to move one of the latter in relation to the other, and exterior means secured to said valve stem by which to rotate the same.

Signed at 132 Nassau street, in the bor-

ough of Manhattan, county of New York, city and State of New York this 24th day of 10 February, 1920.

HENRY SELLMAN.
